UNITED STATES PATENT OFFICE.

CARL EKBERG, OF EVERETT, WASHINGTON.

IMPACT-TOOL.

1,175,621.

Specification of Letters Patent. Patented Mar. 14, 1916.

Application filed February 3, 1915. Serial No. 5,893.

To all whom it may concern:

Be it known that I, CARL EKBERG, a citizen of the United States, and a resident of Everett, in the county of Snohomish and 5 State of Washington, have invented a new and Improved Impact-Tool, of which the following is a full, clear, and exact description.

This invention relates to improvements in 10 impact tools wherein a reciprocating piston is operated by fluid pressure, such as compressed air, and in which the piston serves the purpose of a hammer to strike successive and numerous blows against the tool 15 shank for cutting, calking or riveting in metal or stone work and various other purposes.

A further object of the invention is to provide an improved impact tool or air hammer 20 by which the elimination of complicated valve structures is accomplished for all sizes of tools, varying from the stone mason's engraving hammer, which is very light, up to the ordinary chipping and calking 25 hammer, as well as riveting hammers, and the invention is characterized by the use of a throttle to control the supply of motive fluid, such as compressed air, steam or analogous elastic fluid pressure, to the casing of 30 the tool for the actuation of a hammer piston therein, the casing and piston being provided with a novel arrangement of ducts or ports and passages whereby the hammer is under direct pressure on its forward and 35 return strokes and exhaust from either end is arranged to provide a cushion at the limit of each stroke whereby shocks and jars incident to a device of this character are reduced to a minimum, inoperation of the device 40 obviated and the manual manipulation of the tool by the operator greatly facilitated.

With the above and other objects in view, the invention resides in the peculiar combination and arrangement of parts to be hereinafter more fully described, illustrated 45 and claimed, it being also an object to provide a device which is simple in construction, durable and efficient in operation and 50 not likely to get out of working order.

Reference is to be had to the accompanying drawings forming a part of this specification, in which similar characters of reference indicate corresponding parts in 55 all the views and in which—

Figure 1 is a side elevation of an impact

tool or air hammer constituting my invention; Fig. 2 is a longitudinal sectional view thereof with the piston of the hammer in a position prior to its movement on a forward or operative stroke; Fig. 3 is a similar view thereof with the piston in a position prior to its return stroke; Fig. 4 is a cross sectional view taken on the line 4—4 of Fig. 3; Fig. 5 is a cross sectional view 60 taken on the line 5—5 of Fig. 3; Fig. 6 is a longitudinal sectional view of the casing of the hammer at right angles to Fig. 2; Fig. 7 is a detail elevation of the piston.

In the drawings, the numeral 10 designates the handle of the impact tool or hammer which may be of any preferred design but which is shown shaped in the manner of the handle of a pistol or revolver and adapted to fit the curvature of the hand when grasped for manually operating the device. This handle is of angular or curved 70 form and is designed to be grasped by one or both hands of the operator as distinguished from the use of the ordinary saw 75 style of handle commonly employed in this type of tool. Furthermore, the handle is provided with a longitudinal feed passage 11 which is adapted to be placed in communication with a flexible or other feed pipe or tube 12 having threaded connection therewith, as shown at 13, whereby the tool can be attached or detached at will. The other end of the handle is in the nature of a 80 socket 14 the lateral wall of which is 85 inferiorly threaded while the passage 11 communicates with said socket.

In order to control the supply of motive fluid, preferably compressed air, from the 90 passage 11 to said socket a throttle or valve 95 15 is provided, the same being of circular cross section and snugly movable in a transverse opening 16 of corresponding cross section in the enlarged or sleeve portion of the handle producing the socket 14. The 100 opening 16 is drilled or otherwise formed from one side of the handle and terminates short of the other side at a diametrically opposite point where a restricted opening 17 is provided in such a manner that the valve may be fitted in the opening 16 and the stem portion 18 thereof caused to extend through the reduced opening 17 after which an operating button 19 is mounted on said 105 stem to permit actuation of the valve or throttle by reversion or depression of the same in the opening 16. This opening is 110

then closed by a plug 20 which may be threaded thereinto, and the valve, which is of relatively cylindrical form, has an annular groove 21 in its peripheral surface 5 and an end recess 22 forming a seat for an expansible coiled spring 23 which is disposed between the plug and the end wall of said recess so as to hold the valve toward the end wall of the opening 16 through 10 which the reduced opening 17 is provided and thus hold the valve or throttle, and more particularly the operating head or button thereof, projected from the handle.

The valve is of less length than the length 15 of the opening 16 so as to be adapted for movement therein and when held in the position mentioned by the spring 23 the passage 11 will be closed so as to cut off communication through the same but permit 20 said communication to be made upon the throttle or valve being repressed against the action of the spring to align the groove 21 with said passage, as shown in Fig. 3 of the drawings. The plug 20 is provided with an 25 opening 24 through which such motive fluid or air as may have escaped between the throttle and the plug 20 may pass out to the atmosphere in order to prevent the formation of an air pocket and requiring 30 compression thereof as a hindrance to the movement of the throttle or valve 15 to an open or operative position.

Secured in the threaded socket of the handle is a tool holding casing 25 with 35 which the shank portion 26 of a tool 27 has sliding connection, this being effected through the instrumentality of a plug or nose piece 28 fitted in the open end or nose of the casing and having limited displacement 40 therein through the medium of an internal annular rib 29 and an outer flange on said nose piece. The casing is provided with a longitudinal bore producing a chamber 30 for accommodating a piston 31 which 45 serves as a hammering medium, and the shank portion 26 of the tool extends partly into the chamber 30. The other end of the casing is closed by a cylindrical disk 32 which is fitted in the sleeve portion of the 50 socket and clamped tight against the end of the casing when the latter is secured in the socket, the disk 32 having a stepped face 33 which provides a space at the adjacent end of the casing. The disk 32 which constitutes 55 a closure for the bore of the casing at the handle end thereof is secured to the casing by a locking pin 32' which holds the disk against rotation while the clamping thereof as described and shown holds the 60 same in air tight connection with the casing.

The piston is of cylindrical form but is provided with an axial longitudinal chamber or passage 34 which terminates short of the ends of the piston and which is preferably 65 made by drilling through the rear end

of the latter and closing said bore by a plug 35. The piston is further provided with a pair of longitudinally spaced annular channels 36 and 37 respectively, which are placed in communication with the chamber 34 near 70 the ends of the latter through the instrumentality of a series of radial ducts 38 and 39 respectively. Leading longitudinally through the wall of the casing at one side and communicating with the socket space 75 are a pair of feed passages 40 having inlet ports 41 communicating with the piston chamber 30 nearer to the rear end of said chamber than the forward end thereof, while communication is established centrally 80 with said chamber through the medium of auxiliary inlets 42. Diametrically opposite, or in other suitable relation to the passages 40, the casing is provided with longitudinally extending ports or ducts 43 and 44 respectively, the same being spaced apart centrally of the casing and the former leading to opposite ends of the piston chamber and having lateral end portions connecting the same with said chamber. The duct 43 has 85 communication with the piston chamber additionally through an auxiliary inlet 45 near the end of said duct remote from the handle.

In the operation of the device as described, and with the parts in the position shown in Fig. 2 of the drawings, the throttle valve 15 normally prevents the admission of air or other motive fluid to the interior of the casing for reciprocating the piston therein, but upon the throttle valve being depressed air will be admitted to the feed passages 40 and will escape through the ports or ducts 41, channel 37 and ducts 39 into the passage or chamber 34 and then through the ducts 39 and channel 36, through the lateral portions of the ducts 43 to move the piston forwardly to the position shown in Fig. 3 of the drawings. Under the direct pressure and assisted by its momentum the piston, acting as a hammer, will be carried beyond the last named position to strike the shank of the tool and impart an operative blow to the latter, but as the piston assumes the position shown in Fig. 3 air will escape into the opposite end of the chamber 100 in the casing through the channel 36, passage 34 and channel 37 by the ducts connecting the same, and then through the passages 44 through the medium of the lateral extensions of the latter. In this manner this piston will be acting against direct pressure prior to or after the delivery of the blow or impact so that the action thereof will be materially cushioned to avoid jars and shocks being transmitted to the operator, 110 and in addition to quicken the return of the piston and form efficient means for timing the stroke of the latter and the speed of reciprocation thereof.

When the piston has traveled forwardly 130

a distance equal to the length of the recessed air space in the piston the air is cut off, the channels 36 and 37 at this time straddling the inner lateral ducts or extensions of the passages 44, as shown in dotted lines in Fig. 2 of the drawings, and as the piston is returned under the action of direct pressure by the escape of the air forwardly thereof and the parts are in the 10 position shown in Fig. 3 of the drawings, the exhaust takes place through the diametrically opposite exhaust ports 46 and through longitudinal exhaust passages 47 communicating with the forward end or 15 nose of the casing so as to discharge the exhaust air away from the operator. The stroke is then continued as heretofore described, the exhaust on the forward stroke taking place through exhaust ports 48 com- 20 municating with the passages 47 near the rear ends of the latter, the passages 47 extending longitudinally throughout the greater portion of the length of the casing, as is more particularly shown in Fig. 6 of 25 the drawings.

In order to prevent the piston or piston hammer from stopping on the dead center or remaining in a position where neither one of the channels 36 or 37 is placed in 30 communication with the feed passage 40, if the piston should ever happen to stop where the air will be shut off, that is, in a central position as shown in dotted lines in Fig. 3 of the drawings, the feed passage 40 will be placed in communication with either 35 of the passages 43 or 44 through the instrumentality of the auxiliary inlet ports or ducts 42 and 45, and in this manner air will be admitted for moving the piston toward 40 the port which acts as a supply port, depending upon the direction of the stroke or movement of the piston. On the return stroke of the piston the parts will be in the position as shown in Fig. 2, so that air will 45 be admitted in rear of the piston to act as a cushion and otherwise as heretofore described in connection with the forward movement or stroke of the piston.

In practice all of the parts are preferably 50 made of tool steel except the handle which will be made of mild steel, while the piston, the throttle and the nose piece or plug will be of hardened steel, the handle being of any convenient or desired shape. The sizes 55 of the devices may vary according to the work required but by way of explanation it may be said that in an impact tool or hammer in which the piston weighs about two and one half ounces 3500 or more blows per 60 minute will be struck, and the hammer can be operated to strike a very light blow as the balance obtained is easily regulated by regulating the force of the air through the medium of the throttle.

Having thus described my invention, what

I claim as new and desire to secure by Letters Patent is:—

1. An impact tool, comprising a tool holding casing having sliding connection with the tool employed and provided with a piston hammer chamber, a reciprocating piston hammer mounted in the chamber and having an intermediate axial passage with ducts branching therefrom and external annular channels adapted to be placed under 70 fluid pressure, an inlet port to be placed successively in communication with said channels, exhaust ports which are opened and closed by the piston hammer and longitudinally extending ducts leading from 75 points in spaced relation adjacent to the central part of the chamber to the ends thereof and placed in successive communication with different annular channels so as to be alternately supplied with fluid pres- 80 sure for action against the piston hammer to reciprocate the latter.

2. An impact tool, comprising a tool holding casing having sliding connection with the tool employed and provided with a piston hammer chamber, a reciprocating piston hammer mounted in the chamber and having an intermediate axial passage with ducts branching therefrom and external annular channels adapted to be placed under 90 fluid pressure, an inlet port to be placed successively in communication with said channels, exhaust ports which are opened and closed by the piston hammer, longitudinally extending ducts leading from 95 points in spaced relation adjacent to the central part of the chamber to the ends thereof and placed in successive communication with different annular channels so as to be alternately supplied with fluid pressure for 100 action against the piston hammer to reciprocate the latter and serving at intervals to admit fluid pressure at the non-pressure end of the piston hammer to cushion the latter at the limits of its strokes toward and away 105 from the tool after the actuation of the piston hammer by direct pressure and means for controlling the supply of fluid pressure to the inlet port.

3. An impact tool of the class described, 115 comprising a casing having a longitudinal bore producing a chamber, the nose of the casing having a sliding connection with the tool employed, said casing having an inlet passage designed to be placed in communica- 120 tion with the fluid pressure supply and having communication with the chamber to one side of the longitudinal center thereof, spaced passages in the casing for communica- 125 tion with the chamber of the latter at points spaced apart and at either side of the point of communication of the inlet passage therewith and at the ends of said chamber, a piston mounted to reciprocate in the chamber and having a pair of spaced 130

channels placed in communication with each other at all times through the piston, said piston when in one position serving to admit fluid pressure to one end of the chamber for forcing the piston in the opposite direction and for similarly supplying fluid pressure to the other end of the chamber when in the last named position by causing said channels to be successively and alternately placed in communication with the inlet passage and the last named passages communicating with the chamber at either side of the feed passage and at the ends of said chamber to reverse the position of the piston after the latter has struck the tool and exhaust passages communicating with the chamber for exhausting the fluid pressure at the end of each stroke, said passages having longitudinal portions communicating with the nose end of the casing.

4. An impact tool of the class described, comprising a casing having a longitudinal bore producing a chamber, a tool having sliding connection with the nose of the casing and limited in its displacement therein, said casing having an inlet passage designed to be placed in communication with the fluid pressure supply and having communication with the chamber to one side of the longitudinal center thereof, spaced passages in the casing for communication with the chamber of the latter at points spaced apart and at either side of the point of communication of the inlet passage therewith and at the ends of said chamber, a piston mounted to reciprocate in the chamber and having a pair of spaced channels placed in communication with each other at all times through the piston, said piston when in one position serving to admit fluid pressure to one end of the chamber for forcing the piston in the opposite direction and for similarly supplying fluid pressure to the other end of the chamber when in the last named position by causing said channels to be successively and alternately placed in communication with the inlet passage and the last named passages communicating with the chamber at either side of the feed passage and at the ends of said chamber to reverse the position of the piston after the latter has struck the tool, exhaust passages communicating with the chamber for exhausting the fluid pressure at the end of each stroke, a disk closing the bore of the casing at one end and limiting the movement of the piston toward said end with a space therebetween, means for controlling the supply of fluid pressure to the feed passage of the casing, and auxiliary inlet ducts establishing communication with the feed passage and with either of the passages leading to the chamber at the end of the casing, the said auxiliary ducts being placed in communication with said channels of the piston when

the piston is in a central or dead center position, whereby the piston will be moved toward the port of the passage to be placed into communication therewith on the next stroke.

5. An air hammer, comprising a casing having a circular longitudinal bore, a tool, having sliding connection with the casing at one end, a closure for the other end of the casing, said casing having an inlet port for the fluid pressure supply and having longitudinal inlet passages communicating with the inlet port and having communication with the chamber produced by said bore near the center thereof, said casing at an apsite point being provided with longitudinal passages spaced apart at their inner ends and communicating with the ends of said chamber and with exhaust ports communicating with the tool end of the casing, a cylindrical piston mounted to reciprocate in the chamber to form a hammer, said casing having auxiliary ports establishing communication between the inlet passages and the last named passages leading to the end of the casing having the closure, beyond the points of communication thereof with the chamber, said piston having a longitudinal passage terminating short of the ends thereof, spaced annular grooves and a plurality of radial ducts connecting the passage and grooves, said grooves being alternately placed in communication with the inlet passages and the inlet ends of the other passages, alternately supplying compressed air to the ends of the chamber for reciprocating the piston and serving at each stroke to admit direct air pressure counter to the moving force in a predetermined relative degree to the impact of the piston with the tool, whereby the operation of the piston may be regulated, the exhaust taking place near the limit of each stroke.

6. An impact tool, comprising a tool holding casing, having a longitudinal bore forming a chamber, a tool having sliding connection with the casing, a reciprocating piston hammer mounted in said chamber and having an axial passage closed at each end and ducts branching from said passage, the piston hammer having external annular channels spaced apart and communicating at all times with each other through the said ducts and the axial passage of the piston hammer, the said casing having an inlet port and a longitudinally extending inlet passage communicating with the inlet port and having communication with the chamber of the casing to one side of the longitudinal center thereof, the said casing also having longitudinal passages for communication with the casing chamber at points spaced apart and at either side of the point of communication of the inlet passage with said chamber, the said last mentioned passages

- leading to the ends of the casing chamber, the said annular channels being adapted to be placed successively in communication with the said inlet passage, and the said 5 last mentioned passages being placed in successive communication with different annular channels to be alternately supplied with fluid pressure for action against the piston hammer to reciprocate the same, the 10 said casing having auxiliary ducts for establishing communication through the piston hammer between the inlet passage and one of said last mentioned passages when the piston hammer is in a dead center position, and means for controlling the supply 15 of fluid pressure to the inlet port, said casing having exhaust ports opened and closed by the piston hammer.
7. An impact tool, comprising a tool holding casing having a longitudinal bore forming a chamber, a reciprocating piston hammer mounted in said chamber and having an axial passage closed at each end, the piston hammer having external annular channels 20 spaced apart and communicating with each other through the piston hammer, the 25
- said casing having an inlet passage for the fluid supply having communication with the chamber of the casing, the said casing also having passages for communicating with the casing chamber at points at either side of the point of communication of the inlet passage with said chamber, the said last mentioned passages leading to the ends of the casing chamber, the said annular channels being adapted to be placed successively in communication with the said inlet passage, and the passages leading to the ends of the casing chamber being placed in successive communication with different annular channels to be alternately supplied with fluid pressure to reciprocate the piston hammer, said casing having exhaust ports controlled by the piston hammer.
- In testimony whereof I have signed my name to this specification in the presence of two subscribing witnesses.
